UNITED STATES PATENT OFFICE.

EDWARD J. GULICK, OF MISHAWAKA, INDIANA.

GAS-ENGINE.

No. 923,046.

Specification of Letters Patent.

Patented May 25, 1909.

Application filed May 27, 1907. Serial No. 375,976.

To all whom it may concern:

Be it known that I, EDWARD J. GULICK, a citizen of the United States, residing at Mishawaka, in the county of St. Joseph and State of Indiana, have invented certain new and useful Improvements in Gas-Engines, of which the following is a specification.

My invention pertains to gas engines in general, but particularly relates to a gas engine of the two-cycle type wherein two cylinders are cast integral with bypass, inlet and intake ports for each cylinder situated upon the same side of the engine, the inlet ports being connected by one common inlet chamber which distributes to both cylinders, while the bypass ports are separated for distribution to the respective cylinders. This construction of the inlet ports and inlet chamber affords one common mixing chamber for two cylinders by taking the gases in through one common inlet, while in the single inlet port construction the gases incoming from the carbureter have to be taken through openings in each of the cylinders compelling the same to pass through a greater number of turns in the piping which causes an increase of the fluctuation of the gases and prohibits accurate regulation thereof.

A further advantage is in that the bypass, as just described, permits access to the screens for ease in cleaning and repairing, and also allows a conical screen to be used which gives a very large area for the gases to pass through, as well as avoids the breakage of screens, which is common with the flat type. This breakage of the flat screens is caused by the whipping due to the rapid impulse in passing the gases therethrough.

Further advantages of the construction herein shown will appear in the specification and in the drawings in which,

Figure 1 is a vertical section through one of the cylinders and the crank-chamber embodying my invention; Fig. 2 is a vertical section through one of the cylinder-castings embodying my invention; Fig. 3 is a cross-section on line 3—3 of Fig. 2, assuming the two cylinders to be complete; Fig. 4 is a vertical section through the two integral cylinder-castings embodying my invention; and Fig. 5 is a cross-section on line 5—5 of Fig. 4, assuming that the two cylinders are complete.

The general features of the construction of the gas engine are of the common form,

consisting of cylinders 6, water jacket 7, crank case 8, piston head 9, piston rod 10, crank shaft 11, carbureter 12, radiation pipe 13 for the water jacket, spark plug 14, 60 and pet cocks 15.

In casting the two cylinders integral a lateral passage 16 is left on one side thereof, and substantially intermediate the length of the lateral passage is a port 17 within which is a pipe 18, connected to the wall thereof in any suitable manner, so that gases from the carbureter are admitted directly into the common inlet chamber 16 through the port 17. A series of apertures or inlet ports 9 are 70 further provided, which communicate with the crank case 8, whereby the gases from the carbureter are drawn through a single opening into the common inlet chamber, and from there through the ports 19 into the crank 75 case. By constructing the two cylinders with the common inlet chamber therebetween and on one side thereof the carbureter may therefore have a single communication with the inlet chamber for both cylinders, 80 whereas, heretofore, it was necessary to have two communicating passages or pipes leading from the carbureter to the respective cylinders of the engine. Formed integral with the cylinders are the bypasses 20 and 85 21 that have an opening at their lower ends into the crank case, as shown at 22, and bow out around the common inlet chamber connecting above the same with the explosion chamber of the engine by means of the intake ports 22^a. In the preferred form each cylinder is provided with four intake ports that communicate directly with the bypasses. Within each bypass is a cone-shaped screen 23, or there may be two, as shown at 24, the 90 apex of which extends downward into the bypass and their peripheries resisting upon a circumferential flange 25 within the same, there being a cap 26 to hold said cones in 100 their proper position upon the circumferential flange, and the top of the bypass is provided with a threaded opening 27. Adapted to be screwed within said threaded opening is a plug 28. Interposed between the plug 28 and the cap 26 is a spring 29, the object 105 of which is to keep the cones normally seated but to afford a spring seat for the same as the impulse of the engine tends to unseat the cone, and a spring seat therefore renders them less liable to be broken. The object of 110 providing a conical screen is to prevent whipping thereof under the impulse of the

engine, which also renders them less liable to be broken.

On the opposite side of the cylinder 6, from which the intake ports are situated, are 5 the exhaust ports 30, there being herein shown two exhaust ports for each cylinder that are inclosed by an annular boss 31 formed integral with the cylinder and to which is adapted to be connected a suitable 10 pipe to conduct the exhaust gases away, as into a muffler or the like. Upon the piston head 9 a deflector 32 is formed integral therewith, for a purpose hereinafter described.

The engine operates as follows:—Assum- 15 ing gases to have been admitted into the explosion chamber 33 the piston head 9 would move upward compressing the gases therein, which upward movement would form a suc- 20 tion within the crank chamber drawing a new charge or mixture through the pipe 18 from the carbureter 12 into the common mixture chamber 16 and through the ports 19 into the crank chamber, whereupon the piston having moved to the full extent of 25 its stroke, to compress the gases, the charge would be fired and the piston head moved downward entraining the exhaust gases out through the ports 30 which would then be opened by the downward movement of the 30 piston head and at the same time opening the intake ports 22^a but closing the inlet ports 19 so that gases within the crank chamber would be compressed forcing the same through the opening 22, through the screens, 35 and through the bypasses 20 and 21 and the ports 22^a into the compression chamber, the gas being directed upward along the wall of the cylinder by reason of the deflector 32.

The action in the engine shown and de- 40 scribed for the discharge of the waste gases and for the admittance of the mixture within the explosion chamber is the same as in any two-cycle gas engine wherein the down- 45 stroke of the piston is employed to force a mixture within the crank chamber into the explosion chamber, it being understood that the features of this invention relate alone to the formation of two integral cylinders hav- 50 ing a common chamber for the inlet of the mixture from the carbureter and distribut-

ing it therefrom into the crank chamber, as well as the construction of the bypasses which are also formed integral with the engine proper, said bypasses and common inlet chamber all being situated upon the 55 same side of the engine.

It is not thought necessary to go more into detail in regard to the general features herein shown. It may be stated, however, that 34 is an air intake pipe for the carbureter; 35 an adjustment for controlling the mixture in the carbureter; and that the water jacket, or any of the connections thereto constitute no part of this invention. It is further to be understood that the in- 60 vention is not limited to casting two integral cylinders with a common inlet chamber and integral bypasses for each cylinder, but that any number of cylinders may be cast integral having a common inlet cham- 65 ber and integral bypasses for each cylinder, as herein shown and described, and operating the same, and, therefore, without limiting myself to the construction herein shown,

75

I claim:

1. A two-cycle gas engine having a plu- 70 rality of integral cylinders, a common gas inlet chamber formed integral with said cylinders, and bypasses formed integral with each cylinder, said gas inlet chamber and 80 bypasses being situated on the same side thereof and in communication with the crank case of said engine, substantially as described.

2. A two cycle gas engine having a plu- 85 rality of integral cylinders and a common crank chamber, a common inlet chamber having a single opening for the admittance of a gaseous mixture therein, a plurality of ports in said cylinders for admitting said 90 gaseous mixture therein and a bypass com- 95 municating with said crank chamber and each cylinder, said common inlet chamber and bypasses being situated on the same side of said engine and formed integral there- with, substantially as described.

EDWARD J. GULICK.
